By his Attorney,
Nelson M. Howard

UNITED STATES PATENT OFFICE

GEORGE N. GORDON, OF BROCKTON, MASSACHUSETTS, ASSIGNOR TO UNITED SHOE MANUFACTURERY CORPORATION, OF PATERSON, NEW JERSEY, A CORPORATION OF NEW JERSEY

MARKING AND GAUGING DEVICE

Application filed March 9, 1922. Serial No. 542,282.

My invention relates to the marking of shoe parts and to a novel form of gauging device which, while capable of more general use, is especially adapted for use in positioning shoe parts, such as insoles, as they are being marked. The invention is herein illustrated as embodied in a device for marking the heel-breast line on insoles for welt shoes, to provide a guide for the operation of the 10 welt, and for other purposes.

Insoles, especially those of the type known as "Economy" insoles, are usually provided with cuts determining the opposite ends of the channel lip and with marks on opposite 15 surfaces approximately at the heel breast line of the finished shoe. These marks and cuts are gauged from the heel end of the insole, but when the insole is afterwards tacked or otherwise secured to a last in the assembling 20 of the shoe it is placed with its toe end in registry with the toe end of the last. Various operations, such as the channeling, result in greater or less distortion of the insole and for this and other reasons the insole is in 25 some cases made somewhat longer than is actually required. In such instances the insole is trimmed down to the proper size after it has been secured to the last. Obviously such a sequence of operations makes it extremely difficult 30 to provide for accuracy in making the marks which designate the heel breast line prior to trimming down the insole.

Moreover, in using "Economy" insoles a canvas reinforcement is secured to the channeled surface of each insole terminating approximately at the heel breast line, and unless considerable care is exercised in placing this reinforcement on each insole it will cover 35 the previously made mark which would otherwise serve as a guide in attaching the welt.

It is an object of the present invention to obviate these and other difficulties by providing a device for marking an insole after it has been trimmed and reinforced. Marking the sole in such a manner provides a clear distinct guide for the operation of attaching the welt. The mark is accurately placed since it is gauged from the trimmed 40 insole, and if the reinforcement extends too

far back the marking extends across the surface thereof where it is in plain sight.

From a different point of view the invention may be regarded as comprising a yieldingly mounted marking device which can 55 adapt itself to an undulating or uneven surface such as the ribbed surface of a channeled and reinforced insole. As illustrated, a marking roller runs in a reservoir of ink and is urged upwardly against the work so 60 that during relative traversing movement of the work and the roller the latter will automatically adjust itself to the varying heights of the different parts of the work.

It is desirable in performing such an operation as indicating the heel breast line to provide an adjustment so that the marking device may be utilized with equal facility, in operations upon the insoles of either men's or women's shoes. A further object of the invention, accordingly, is to provide improved gauging means which can be adjusted for different sizes of shoes, and in which an auxiliary adjustment is provided to change the 65 reading of the device which indicates the position of the gauge proper. In the illustrated device which is hereinafter described, a gauge setting member carries a pointer which co-operates with a scale which is normally fixed, and the scale is arranged to be 70 moved and clamped in different positions, in the present instance the purpose being to change the setting of the gauge according 75 to the size of the shoe. As the device is to be used on insoles for men's or for women's shoes.

Other objects and features of the invention and various novel combinations and improved constructions will be apparent from the following description of an illustrative device shown in the accompanying drawings, 80 in which

Fig. 1 is an isometric view, partly broken away, showing an insole marking device;

Fig. 2 is a section longitudinally through the device shown in Fig. 1; and

Fig. 3 is a perspective showing the heel end of a last with an "Economy" insole attached and with a mark across the insole such as is produced by the machine shown in Figs. 1 and 2.

The improved marking device shown in the drawings comprises generally a suitable support 10, a novel form of gauge 12 mounted on a slide 14 operated by a threaded connection with a rotatable spindle 16 which is manipulated by an operator by means of a knurled hand wheel 18. The slide 14 carries a pointer 20 which co-operates with a scale 22, which is secured to the support 10 by means of a screw 24 extending through a slot in the scale 22. For reasons hereinbefore explained, this scale is illustrated as being arranged to seat against a suitable stop 26 to be positioned for use in operating on insoles for women's shoes or against a second stop 28 for use in operating on insoles for men's shoes. The scale is adapted to be clamped in either of the two working positions referred to by tightening the screw 24. It will be apparent that the gauge 12 may be positioned by an operator according to the reading of pointer 20 on scale 22, and that the operator may then pass insoles across the top of the support 10 with the heel end of each insole in engagement with the gauge 12. In order to gauge from the heel end of an insole, if it is not desired to remove it from a last to which it has been secured, the gauge 12 is provided with a relatively thin vertical portion to engage the insole and is cut away above this vertical portion on a bevel to avoid engagement with the bulge of the last above the insole as shown in Fig. 2. The beveled portion of the gauge 12 affords a convenient means for guiding the sole edge into engagement with the relatively thin vertical portion of the gauge, thereby facilitating the positioning of the insole for the marking operation. As the previously prepared insoles are moved across the top of support 10 as described, each one is provided with an inked line substantially at its heel breast line by a yieldingly mounted marking device illustrated as a roller or wheel 30 carried by an oscillating arm 32 which is urged upwardly against the work by a spring 34. The roller 30 extends upwardly through a suitable slot in the top 36 of an ink reservoir 38 which is arranged so that the lower part of the roller 30 is constantly immersed in the ink contained in the reservoir. When an insole or other uneven piece of work is passed across a marking device of this kind, and a projection such as the sewing rib or the channeled portion of the sole is encountered, the roller 30 yields downwardly in an arcuate direction toward the right and rides over such projection without at any time losing contact with the work. Thus it will be apparent that even when operating on work which is as uneven as channeled and ribbed insoles, a clear and distinct line such as indicated in Fig. 3 at 40 will be formed on each insole 42, shown in that figure as being mounted on a last 44.

While a particular construction has been illustrated and described in explaining my invention it is not my intention to limit its scope thereby or otherwise than by the terms of the appended claims.

Having described my invention, what I claim as new and desire to secure by Letters Patent of the United States is:

1. A device for marking insoles which have been tacked to lasts comprising, in combination, a yieldingly-mounted marking device, means to supply ink thereto, and an adjustable gauge cut away to engage the heel end of an insole without engaging a last to which the insole is tacked. 70
2. A device for marking insoles which have been tacked to lasts comprising, in combination, a yieldingly-mounted marking device, means to supply ink thereto, an adjustable gauge cut away to engage the heel end of an insole without engaging a last to which the insole is tacked, and indicating means for said gauge differently adjustable for men's and for women's insoles. 80
3. A device for marking insoles which have been tacked to lasts comprising, in combination, a yieldingly-mounted marking device, means to supply ink thereto, and means to guide a last and insole as they are moved by an operator across the marking device. 90
4. A device for marking shoe parts comprising, in combination, a rotatably mounted marking wheel, a yielding mounting for the wheel permitting it to move downwardly when engaged by the work but urging it upwardly to maintain it in operative position, and means to position a shoe part during relative traversing movement of the part and wheel. 100
5. A device for marking shoe parts comprising, in combination, a rotatably mounted marking wheel, a yielding mounting for the wheel permitting it to move downwardly but urging it upwardly, an ink reservoir below the wheel to supply ink to the lower portion thereof, and means to maintain in proper position a shoe part during relative traversing movement of the part and wheel. 110
6. A device of the class described comprising, in combination, an instrumentality to operate on a shoe part, an adjustable gauge adapted to position the work with respect to said instrumentality and shaped to guide the work in a straight path, means for adjusting the gauge, a pointer and scale plate, one of which is normally fixed and the other of which moves with the gauge, said pointer and scale plate being relatively adjustable independently of adjustment of the gauge, stops for determining two positions of said relative adjustment, and means for securing the scale plate and pointer in said positions of adjustment. 120
7. A device for marking channeled and ribbed insoles comprising, in combination, 130

a support across which an insole is moved in a widthwise direction, means for positioning the insole while it is being moved across the support, means for marking the insole, 5 a yielding mounting for the marking means enabling the latter to accommodate itself to the varying thickness of an insole across the channeled portion, the ribbed portion, and the unchanneled portion thereof, and an adjusting screw arranged to adjust the insole positioning means relatively to said support and to retain said means in adjusted position. 10 8. A device for marking ribbed insoles comprising, in combination, means for marking an insole, a support upon which the insole may be manipulated to move the rib transversely across the marking means, a mounting for said marking means enabling it to accommodate itself to the varying heights of 15 different parts of the surface of the ribbed insole, a member for guiding the insole in a straight path, and means for adjusting said member toward and from said marking means to vary the location of the mark made 20 by said means on the insole. 25 9. An instrumentality for operating upon an insole mounted upon a last, and a gauge for positioning the insole relatively to said instrumentality, said gauge having a face for engaging the edge of the insole and a beveled portion shaped and arranged to facilitate the engagement of the sole edge with said gauge face and to avoid engaging the bulge of the last above the insole.

25 10. A device for marking insoles which have been tacked to lasts comprising in combination, a support for the insole and last, a gauge adapted to engage the edge of the insole at the heel end thereof while the insole 40 and last are moved across the support, a marking device yieldingly held in the path of the insole, and means for adjusting the gauge relatively to the marking device.

45 11. A device for marking insoles which have been tacked to lasts comprising in combination, a table for supporting the heel end of an insole and last while they are moved in a widthwise direction, means for marking the moving insole and a gauge on said table 50 for positioning the insole relatively to the marking means, said gauge being formed with a guiding face adapted to engage the edge of the insole at the heel end thereof and a beveled face sloping upwardly from said 55 guiding face to avoid the bulge at the rear of the last.

In testimony whereof I have signed my name to this specification.

GEORGE N. GORDON.
